UNITED STATES PATENT OFFICE.

HERBERT S. SIMPSON, OF CHICAGO, ILLINOIS.

AUTOMATIC DEVICE FOR OPERATING AND CLOSING DISCHARGE DOORS ON MIXERS.

Application filed June 28, 1924. Serial No. 723,053.

This invention relates to an automatically operated door for the bowl or mixing receptacle of mixing machines, and comprises a door that is secured to the bottom of the bowl and that is automatically opened and closed during the operation of the machine.

It is an object of this invention to provide suitable mechanism for automatically opening said door, retaining the same open for a predetermined period for the discharge of the mixed material and then automatically closing the same.

The invention consists of the novel structure hereinafter described and more particularly pointed out and defined in the appended claims.

In the accompanying drawings which illustrate a preferred embodiment of this invention, and in which similar reference numerals refer to similar features in the different views.

Figure 1 is an elevational view of a mixing machine involving this invention.

Figure 2 is a fragmentary sectional view of the same.

Figure 3 is an enlarged fragmentary elevational view of the door operating mechanism with parts shown in different positions in dotted lines.

Figure 4 is a view similar to Figure 3 illustrating parts in different positions.

Figure 5 is an enlarged sectional view through the operating mechanism.

Figure 6 is an enlarged bottom plan view of certain driving mechanism.

Figure 7 is an enlarged fragmentary elevational view of the operating counter weight.

Figure 8 is an enlarged top plan view of the driving mechanism for operating the door.

Referring now to the drawings, there is shown certain parts of a mixing machine comprising the usual bowl or drum 1 centrally of which extends a shaft 2 upon which the plows and mullers may be supported as is shown in my co-pending application, Serial No. 499,620. A suitable frame or legs 1^a may support the bowl as shown in Figure 1. A bevel gear 3 is secured upon the shaft 2 for rotating the same, and may be termed the driving mechanism, and a worm disk 4 is secured upon the gear 3 for rotation therewith. The gear 3 may be rotated by any suitable co-operating gear and source of power.

A shaft 5 is suitably supported adjacent the worm disk 4, and a worm gear 6 is secured upon this shaft and meshes with the worm disk 4. A sprocket gear 7 is secured upon the end of the shaft 5, and a sprocket chain 8 is trained thereover and also over a larger sprocket gear 9 journalled upon a shaft 10 suitably supported from the bowl 1. This sprocket chain is provided with laterally projecting studs 11 and 11^a equipped with rollers for a purpose that will later appear.

In referring to Figure 5, it will be observed that a rod 12 is journalled in depending bearing lugs 13 on the bottom of the bowl and which rest upon the legs 1^a. A door 14 is secured upon this rod for normally closing an aperture in the bottom of the bowl. This door consists of a flat portion 14^a that fits in the aperture, and brackets 14^b that extends beyond the flat portion and that are secured upon the rod 12 for rotation therewith. A counter weight 15 is rigidly secured upon one end of the shaft and is normally in a pendant position for retaining the door in closed position. Upon the other end of the rod 12, the ends of which it will be observed project beyond their bearings, there is rigidly secured an arm 16 which is pivoted at its lower end to an intermediate link 17 which is adjustable as to its length due to the lower section being screw threaded into the upper portion. The lower end of the link 17 is pivoted to an arm 18 rigidly secured upon a hollow shaft 19 journalled in the legs 1^a. Thus a form of toggle acting lever is provided. The lower portion of the link 17 is provided with a stop portion 20 that overlaps the arm 18 to prevent flexure in the opposite direction.

The hollow shaft 19 extends beyond the bearing legs 1^a and upon one end thereof there is secured an arm or bracket 21 provided with a pair of spaced lugs 22. Upon the other end of the hollow shaft there is secured a hub 23 provided with a projecting cam 24 which lies in the path of the projection 11^a on the sprocket chain 8 as shown in Figure 8.

A shaft 25 is journalled within the hollow shaft 19 and extends beyond the ends thereof. Upon the end of the shaft 25 adjacent the hub 23, there is secured a hub 26 provided with a projection 27 that lies in the path of the stud 11. A shorter projection

28 is spaced a short distance to the rear of the stud 27 to form a pocket for receiving the stud 11.

Upon the opposite end of the shaft 25 there is rigidly secured a counter weight 29 by means of an arm or bracket 30 splined upon the shaft 25. The arm 30 lies between the lugs 22 upon the bracket 21 and is narrower than the distance between the lugs 10 to allow for a certain amount of play or lost motion for a purpose that will later appear.

The counter weights 15 and 29 are preferably adjustably mounted on their supports by means of set screws or the like so as to obtain the proper difference in balance with the door.

When the mixing apparatus is in operation the sprocket chain will be rotated for 20 opening and closing the door of the bowl through the action of the studs 11 and 11^a. This door will remain open a predetermined period, depending upon the number and spacing of the studs 11 and 11^a.

25 Assuming that the door 14 is closed and the machine is in operation, the sprocket chain 8 will be continuously driven, and when the stud 11 comes around it will engage the projection or finger 27 and rotate 30 the same together with the shaft 25 a predetermined distance of about 90°. This will bring the counter weight 29 upon the opposite end of shaft 25 to substantially a vertical position. It will of course be apparent that after the arm 30 of counter 35 weight 29 has travelled about 10° it will engage the upper lug 22 of bracket 21 and rotate the hollow shaft 19. Rotation of the hollow shaft 19 will break the toggle joint 40 31 between the arm 18 and link 17, which allows the door 14 to drop. The weight of the door acting through the toggle levers will further rotate the hollow shaft 19 and bring the lower lug 22 on the bracket 21 45 against the arm 30 of the counter weight 29, causing the same to move beyond dead center and drop about 10° against the upper lug.

The rotation of the hollow shaft 19 will 50 bring the cam 24 in the path of the roller 11^a as shown in Figure 4. The roller 11^a will hence engage the cam 24 and cause it and the hollow shaft to rotate in the opposite direction. This reverse rotation of 55 the hollow shaft 19 will cause the counter weight 29 to rotate back about 15° through the upper lug 22 on bracket 21, bring the same beyond dead center so that it will be free to drop. As the counter weight thus 60 begins to drop by gravity the arm 30 thereof will engage the lower lug 22 and rotate the hollow shaft to the position shown in full lines in Figure 3. During this drop of 65 the counter weights the toggle lever will raise the door to its closed position with the

toggle levers locked by the stop 20. The door 14 may also be manually opened by lifting the counter weight 29 as is obvious.

It will be apparent that the gravity acting motion is such that should an obstruction tend to prevent the door closing the counter weight continues to exert an upward pressure until the obstruction is removed either by mechanical vibrations or by the operator.

75

I am aware that numerous details of construction may be varied through a wide range without departing from the principles of this invention, and I therefore do not purpose limiting the patent granted 80 otherwise than necessitated by the prior art.

I claim as my invention:

1. In a mixing machine, a bowl, a door in the bottom of the bowl, a rotatable rod for supporting said door, a pair of independent 85 concentric shafts rotatably supported beneath said bowl, a toggle lever connection between said rod and the outer concentric shaft, a counter weight secured upon the inner concentric shaft, a bracket upon the 90 outer concentric shaft having a lost motion connection with said counter weight, a cam secured upon the outer concentric shaft, a finger secured upon the inner concentric shaft, adjacent said cam, and a sprocket chain moving between said cam and finger and having laterally projecting studs for alternately operating said cam and finger for the purpose set forth.

2. In a mixing machine, a bowl, a door in 100 the bottom of the bowl, a rod for pivotally supporting said door, a toggle mechanism connected to said rod, and means for actuating said toggle mechanism for controlling said door.

105

3. In a mixing machine, a bowl, a door in the bottom of the bowl, a rod for pivotally supporting said door, toggle mechanism connected to said rod, and means for periodically actuating said toggle mechanism during 110 the operation of said machine.

4. In a mixing machine provided with a receptacle having a door operating mechanism for said machine, a rotatable rod for supporting said door, a shaft, toggle mechanism connecting said rod and shaft, and means actuated by said operating mechanism for periodically rotating said shaft in opposite directions for opening and closing said door.

120

5. In a mixing machine, provided with a mixing chamber, a door leading to said chamber, operating mechanism for said machine, operating toggle mechanism for opening and closing said door, and a member continuously driven by said machine operating mechanism for periodically operating said toggle mechanism.

125

6. In a mixing machine, having a mixing receptacle provided with a door, a rotatable

130

rod for supporting said door, a shaft, toggle mechanism connecting said rod and shaft, a second shaft, a lost motion connection between said shaft comprising a counter weight, and means for periodically operating said shafts in opposite directions.

7. In a mixing machine having a mixing receptacle provided with a door, driving mechanism for said machine, operating mechanism for said door including a rotatable counter weight, swingable beyond dead center during the opening of said door, and means for swinging said weight in the opposite direction beyond dead center for automatically closing said door.

8. In a mixing machine having a mixing receptacle provided with a door, a rod for supporting said door, a shaft, toggle levers

connecting said rod and shaft, a second rotatable shaft and having a lost motion connection with said first shaft, and means operated by the driving mechanism for rotating said shafts a predetermined amount in opposite directions.

9. In a mixing machine having a mixing receptacle provided with a door, driving mechanism for said machine, operating mechanism for said door, means driven by said driving mechanism for initially actuating said operating mechanism and gravity acting means for completing the actuation of said operating means.

In testimony whereof I have hereunto subscribed my name.

HERBERT S. SIMPSON.
